(57) **CLAIM**

What is claimed is the ornamental design for a disc launcher toy, as shown and described.

DESCRIPTION

FIG. 1 is a top, front, and right perspective view of a disc launcher toy;

FIG. 2 is a bottom view thereof;

FIG. 3 is a top view thereof;

FIG. 4 is a left view thereof;

FIG. 5 is a right view thereof;

FIG. 6 is a front view thereof; and,

FIG. 7 is a rear view thereof.

The broken lines in the drawings are included for the purpose of illustrating portions of the disc launcher toy that form no part of the claimed design.
